F. Russell.

Mower.

Nº 13438

Fig. 1. Patented Aug. 14, 1855.

Fig. 3

UNITED STATES PATENT OFFICE.

FISK RUSSELL, OF BOSTON, MASSACHUSETTS.

IMPROVEMENT IN HARVESTERS.

Specification forming part of Letters Patent No. 13,438, dated August 14, 1855.

To all whom it may concern:

Be it known that I, FISK RUSSELL, of Boston, in the county of Suffolk and State of Massachusetts, have invented an Improvement in Grass-Harvesters; and I do hereby declare that the same is fully described and represented in the following specification and the accompanying drawings, letters, figures, and references thereof.

In said drawings, Figure 1 represents a top view of that portion of my machine to which my improvement relates. Fig. 2 is a side elevation taken on that side on which the cutter-bar is situated. Fig. 3 is a side view of the inclined lever G when taken out of the machine and the rocker frame turned one-fourth round.

The driving-shaft E (denoted in Fig. 1) carries a pinion, D, which plays into the internal gear of the driving-wheel. This driving-shaft extends across the frame and is supported in boxes, as seen at c c c, and carries a cam-wheel, F. Said cam-wheel is so formed as to impart a reciprocating vibratory movement to an inclined lever, G, which works on a fulerum at H. The lower end of said lever passes into a mortise in an iron rod, which is made to work the knives, while the upper end of said lever

carries a bifurcated rocker-frame, I, that is made to turn in the end of the lever, and embraces the serpentine edge of the cam-wheel, and supports two friction-rollers, d e, placed on opposite sides of and against the cam-wheel.

By means of the rocker-frame the cam-wheel is enabled to operate the lever to much better advantage and with less noise and friction than would be the case were the lever applied to the cam-wheel by a stationary fork or its equivalent. Besides this, another advantage results from the peculiar application or use of a rocker-frame—viz., that it accommodates itself to the course of the cam-wheel, so as to prevent improper lateral strain on the lever.

What I claim, and wish to secure by Letters Patent, is—

So arranging the rocker-frame I that it may rotate in the end of the lever G while said rocker-frame is operated upon by the serpentine cam-wheel, which it embraces, essentially as specified.

In testimony whereof I have hereunto subscribed my name.

FISK RUSSELL.
